UNITED STATES PATENT OFFICE.

AARON A. GOLDSTEIN, OF BUFFALO, NEW YORK.

FASTENER FOR BRACELETS.

Application filed November 23, 1925. Serial No. 70,870.

The principal objects of the invention are to provide a cheap form of bracelet for securing wrist watches which will be very flexible, will present a good appearance and will fit snugly to the wrist of the wearer and the ends of which will be fastened securely to the bracelet member.

The principal feature of the invention consists in securing fastening members to the ends of a length of elastic on which are threaded a number of rings.

In the drawings, Figure 1 is a plan view of the outer side of a bracelet constructed in accordance with this invention.

Figure 2 is an underside plan view of the bracelet shown distended.

Figure 3 is an enlarged longitudinal sectional detail view through the clasp and one of the rings encircling the elastic fabric.

Expansible link bracelets of many different forms of structure have been devised for securing wrist watches but they vary in their degrees of flexibility, expansibility and strength, and constitute a plurality of interlocking units. Such constructions are more or less costly and it is desirable to produce a cheap form of bracelet which will present a very good appearance and will be quite dependable.

In the present invention a length of elastic fabric 1, preferably silk of a suitable length to snugly encircle the wrist has securely fastened to either end a spring clasp 2 of a suitable design to engage the holding loops 3 of a watch. The clasps 2 are formed of sheet metal having a box-shaped portion 3 to receive the end of the elastic strip. The box

portion 3 has a tongue 4 punched from the under side 5 to engage and grip the elastic fabric securely.

Bands 6 formed of sheet metal strips having the ends bent inwardly are threaded on to the elastic strip and present an appearance similar to the links of a chain link bracelet.

Such a construction is extremely simple and a bracelet may be made in very attractive form at very low cost or it may be found desirable to use precious metals for the bands and hooks. In either case, the bracelet has a remarkable range of expansion and as the elastic may deteriorate through use and time it may be very readily removed from the metal parts, it being merely necessary to lift the gripping tongue 4 to release the end hooks and slip the bands off when they may be readily placed on a new piece of elastic.

A further feature of advantage in the adoption of the present invention is that the bracelet may be made very much thinner than those in which the various links are mechanically connected.

What I claim as my invention is:—

A fastener for bracelets of the flexible fabric type, formed of a strip of sheet metal having one end bent to form a hook and formed with side flanges turned inwardly, a metal plate secured between the inturned side edges of said strip and retained by said flanges, said plates having a rectangular-shaped lug struck therefrom to project inwardly and engage and grip the surface of the end of the fabric strap inserted between the flanges.

AARON A. GOLDSTEIN.
